UNITED STATES PATENT OFFICE.

ALFRED KITCHEN, OF DUNNVILLE, CANADA.

ROTARY ENGINE.

SPECIFICATION forming part of Letters Patent No. 681,919, dated September 3, 1901.

Application filed January 31, 1900. Serial No. 3,492. (No model.)

To all whom it may concern:

Be it known that I, ALFRED KITCHEN, carpet-manufacturer, of the village of Dunnville, in the county of Haldimand, in the Province 5 of Ontario, Canada, have invented certain new and useful Improvements in Rotary Engines, of which the following is a specification.

My invention relates to improvements in rotary engines; and the object of the invention is to devise a simple, compact, and steam-tight rotary engine in which, first, the power may be transmitted directly from the periphery of the engine; secondly, in which the steam may be introduced into the interior of 15 the engine at a point where there is no danger of condensation while passing through the engine, and, thirdly, in which the strain on the bearings of the rotating portion may be reduced to a minimum; and it consists, essentially, of a stationary hollow shaft, both the 20 inlet and exhaust ports of which lead to the inlet and exhaust ports in a solid cylinder, such cylinder being eccentric to the axis of the hollow shaft and being surrounded by a 25 rotatable cylinder, forming a crescent-shaped chamber between it and the stationary cylinder, such rotating cylinder carrying wings, which are caused to follow the periphery of the eccentrically-placed solid cylinder by 30 means of suitable eccentrics on the shaft to which they are connected; and the latter cylinder having connected to it a suitable peripheral casing, which is supported at the ends on suitable bearings on the shaft and 35 is designed to rotate with it, the parts being arranged and constructed in detail as hereinafter more particularly explained.

Figure 1 is a cross-section of my improved rotary engine. Fig. 2 is a longitudinal section. Fig. 3 is a detail of the governor in the form shown in Figs. 1 and 2. Fig. 4 is a longitudinal section of a compound or double-cylinder form. Fig. 5 is a detail of the reversing-plug used in the compound form. 45 Fig. 6 is a plan view looking from below of the center solid cylinder used in the reversing form, showing the position of the ports in the solid cylinder and in dotted lines the position of the inlet passage-ways leading to 50 such ports.

In the drawings like characters of reference indicate corresponding parts in each figure.

A A' are the standards.

B and B' are the hollow portions of the divided shaft, which are suitably keyed, as indicated, in the standards, so as to prevent them from rotating and have attached to or forming part of them at the inner end the solid cylinder B², which is, as will be seen, eccentric to the shaft. 55

b and b' are the exhaust and inlet pipes, which lead through the hollow portions B and B' to the interior of the cylinder B² near its center, as indicated. The pipes b and b' are surrounded by suitable packing 2, made 60 of mineral wool, asbestos, or other suitable heat-non-conducting material. 65

C is the inlet-port, and 3 the exhaust-port, (shown in full lines in Fig. 1 and in light and dark dotted lines, respectively, in Fig. 2,) 70 such ports being connected to the inlet-pipe b' and exhaust-pipe b, respectively.

D is the rotating casing, which, it will be noticed on reference to Fig. 1, is concentric to the shaft, but eccentric to the cylinder B², 75 thereby forming a crescent-shaped chamber. Such cylinder is provided with the sides D' and D'', which abut or overlap the cylinder B² and are rendered steam-tight at such point by the packing-rings d' and d''. 80

D³ is the outer casing, attached to or forming part of the inner cylindrical casing D and provided with the recesses d, having suitable caps d³. The casing D³ is also provided with peripheral lugs d⁴, upon which is suitably secured by lugs d⁵ the peripheral pulley or driving-ring D⁴. 85

D⁶ and D⁶ are the ends of the casing D³, which are suitably secured to the same by the bolts d⁶ and are provided with hubs d⁷, which 90 are supported on the bearings d⁸, secured to the standard.

E indicates the radial pistons, which extend through slots f in the cross-plugs F, which have the end packing-disks f' at the end resting in recesses f² in the sides D' of the casing D. 95

f³ is suitable packing on each side of the plugs F.

G is a packing-dog extending across the periphery of the cylinder B² at the point of contact with the interior of the cylinder D. 100

The wings E are provided with lateral projections E', which are connected by the rods

e to the eccentric rings *e'*, which are designed to rotate on the stationary eccentric *e²*. The outer eccentric *e²* in each case extends into the end *D⁶* and is provided with a suitable

5 ring 4.

The form of engine so far described and shown is an engine designed to rotate in the one way only, and in order to regulate its speed I provide in a cylindrical chamber *C'*, intermediate of the length of the port *C*, the rocking valve *C²*. The position of this valve *C²* is regulated by the governor, which consists of the plate *H*, secured to the end *D⁶*, the pivoted weight *h*, connected by the spring *h'* to a hook *h²* on an offset *h³* of the plate *H*, and the rod *h⁴*, connected by the link *h⁵* to the arm *h⁶*, attached to or forming part of the eccentric *h⁷*, which is provided with a stationary strap *h⁸*, connected by the link *h⁹* to the spindle *c* of the valve *C²*. The operation of this governor is merely that the weight *h* is thrown outwardly when the centrifugal force increases, and consequently pulls upon the eccentric *h⁷*, throwing the strap *h⁸* farther

20 from the center at the point where the link *h⁹* is connected, thus turning the valve *C²* on its pivot, so as to close or partially close the port *C*. This of course depends, as in ordinary governors, upon the speed of the engine

25 as to how much of the port is closed.

The operation of my invention is very simple, as the steam enters through the pipe *b'* and port *C*, thereby carrying around the pistons *E*, which are controlled by the eccentric 30 *e²*, so as to follow the periphery of the eccentrically-placed solid cylinder and carry with them the outer cylinder *D*, the steam of course exhausting through the exhaust-port *3*.

In Figs. 4, 5, and 6 I show a compound or 35 double-cylinder engine; but it will of course be understood that I might have a triple or multiple expansion engine adopting the same principle as I shall now describe in reference to these figures. The cylinder *B²* in these

40 latter figures is formed in two portions *B³* and *B⁴*, and the crescent-shaped chambers are separated by a ring *B⁵*, having suitable packing *b²* abutting the ring *B⁵*, so as to keep the space between the chamber steam-tight.

45 I form a tapered hole *B⁷* in the portions *B³* and *B⁴* and provide a tapered plug *I* to fit the same, which has an extension pipe or tube *b³* extending through the packing *2*. This pipe has a shoulder *4'*. The ring *5*, provided with 50 a handle *6*, has an external thread which fits into a corresponding recess in the standard. A ring *7*, provided with a handle *8*, is keyed to the pipe and abuts the ring *5*. The pipe *b³* is capable of being turned and is provided

55 with a suitable universal coupling *9*, by which it is connected to an exhaust-pipe *10*. The passage-way *i* from the pipe *I* extends into the plug *B⁷* about midway of the length of the portion *B⁴*, and the passage-way from the

60 inlet-pipe *B^a* extends into the plug *B⁷* at the opposite end about midway of the length of the portion *B³*. The plug is provided with

an inlet-port *B^c*, extending into the passage-way *B^a*, and a port *B^d*, connected by a serpentine groove *B^e* to the controlling-port *B^f*, 70 which is in the path of the ports in the cylinder. A port *B^g* is provided at the opposite end of the plug, which is opposite the inlet and exhaust ports *C* and *3* in the portion *B⁴*. This plug is specially designed to form a reversing plug, and consequently is provided with a duplicate of the portions *B^c*, *B^d*, *B^e*, *B^f*, and *B^g*, the only difference being that the portions *B^d*, *B^c*, and *B^f* are reversely formed 75 on the side of the plug, which is not shown 80 in Fig. 5, but which is indicated in Fig. 6, the portions shown in Fig. 5 being indicated by heavy dotted lines and the portion not shown by light dotted lines. The steam is introduced through the port *B^c* and passes 85 around through the port *C* (which in this instance would have no valve *C²*) and around the crescent-shaped chamber, carrying with it the wings and outer casing to the exhaust-port *3*, from which it passes back into the 90 plug *I* into the port *B^d*, thence by the passage-way *B^e* into the inlet-port *C'* of the portion *B⁴*, where it passes around the crescent-shaped chamber again and out through the exhaust-port *3* into the passage-way *B^g* opposite the exhaust, whence it is carried out 95 from the plug *I*. To reverse, the corresponding ports formed on the plug are turned opposite the inlet-ports. In order to turn the plug, however, to reverse, it is simply necessary to loosen the ring *5* by turning the handle *6*, when the handle *8* may be manipulated so as to turn the plug, when the said ports may be restored to their normal position, so as to push the plug home again and hold it 100 rigid.

From the construction I have described it will readily be seen that I can form with equal facility a simple or compound engine and can reverse such engine whether compound, triple, or multiple expansion. The steam is introduced into the engine at a point where it is not likely to be condensed, which is a decided advantage, and it also expands within a heated cylinder, thereby economizing the steam. Extra pulleys and standards are dispensed with as the power is transmitted from the periphery of the cylinder. In applying the power by a belt of course the direction of the pull of the belt would be from 110 the wide side of the crescent-shaped chamber, thereby reducing to a minimum the strain on the bearings, as of course the greatest pressure is exerted by the steam at the largest point of the crescent-shaped chamber. It 115 will also be seen that my engine is perfectly steam-tight and that should any steam escape from the crescent-shaped chamber it can only escape into the outer casing and the steam-cylinder and will only serve to keep 120 the interior portion hot, but cannot escape completely and be wasted.

In Fig. 4 I show instead of the ball-bearing shown in Fig. 1 another form of bearing,

which it is not necessary here to describe, as there are many forms of bearing which may be adapted to form the bearings of my engine.

5. What I claim as my invention is—

1. In a rotary engine, the combination with the main stationary shaft and the solid cylindrical eccentric portions of the concentric casings having the concentric side plates overlapping the ends of the solid cylindrical portion and the intermediate concentric portion or plate attached to the concentric casing and fitting into a corresponding recess formed between the eccentric solid cylindrical portion as specified and a suitable port leading through the solid cylindrical portion and forming a communicating passage-way between the chambers as specified.
2. In a rotary engine, the combination with the main stationary shaft and the solid cylindrical eccentric portions of the concentric casings having the concentric side plates overlapping the ends of the solid cylindrical portion, suitable ring-packing between the concentric casings and the solid cylindrical portion, the intermediate concentric ring or plate attached to the concentric casings and fitting into a corresponding recess formed between the eccentric solid cylindrical portions and suitable packing-rings in the solid cylindrical portions abutting such intermediate ring on each side and a suitable port leading through the solid cylindrical portion and forming a communicating passage-way between the chambers as specified.
3. In a rotary engine, the combination with the main stationary shaft and the solid cylinder attached to or forming part of same located intermediate of its length, of the inlet and exhaust passage-ways extending through the shaft, the radial inlet and exhaust ports extending therefrom to the periphery of the solid cylinder, the rotating cylinder concentric to the shaft and forming a crescent-shaped steam-chamber supported on suitable bearings and the radial pistons suitably held in the cylinder and provided with lateral offsets outside the cylinder, the stationary eccentric secured to the stationary shaft and the eccentric rotatable straps and rods connected to the offsets of the radial pistons as and for the purpose specified.

4. In a rotary engine, the combination with the main stationary shaft and the solid cylinder attached to or forming part of same located intermediate of its length and eccentric thereto, of the inlet and exhaust passage-ways extending through the shaft, the radial inlet and exhaust ports extending therefrom to the periphery of the solid cylinder, the rotatable cylinder concentric to the shaft forming a crescent-shaped steam-chamber and supported on suitable bearings and the radial pistons suitably held in the cylinder, means for imparting a rotary movement

thereto to follow the periphery of the solid cylinder in their rotation, the valve-chamber and cut-off valve located therein intermediate of the length of the inlet-port, the eccentric on the stationary shaft, the strap surrounding the same and connected by link to the stem of the valve, the arm connected to the eccentric, the weighted arm and rod and link connected to the aforesaid arm and the plate secured to the rotatable casing on which the said weighted arm is pivoted and the spring connecting the weighted arm to said plate all arranged as shown and for the purpose specified.

5. In a rotary engine, the combination with the main stationary shaft and the solid cylinder attached to or forming part of same located intermediate of its length, of the inlet and exhaust passage-ways extending through the shaft, the radial and inlet exhaust-ports extending therefrom to the periphery of the solid cylinder, the tapered hole extending through the solid cylinder, the tapered plug fitting therein and connecting with the inlet and exhaust passage-ways extending through the shaft, the port B^c, the port B^d, the port B^e and port B^f and port B^g designed to coact with the inlet and exhaust ports extending through the portions of the cylinder, the rotatable cylinder concentric to the shaft, the division-ring situated between the two ends of the cylinder and forming two crescent-shaped steam-chambers, the radial pistons and means for imparting a radial movement thereto to follow the periphery of the solid cylinder in their rotation as and for the purpose specified.

6. In a rotary engine, the combination with the main stationary shaft and the solid cylinder attached to or forming part of same located intermediate of its length, of the inlet and exhaust passage-ways extending through the shaft, the radial and inlet exhaust-ports extending therefrom to the periphery of the solid cylinder, the tapered hole extending through the solid cylinder, the tapered plug fitting therein and connecting with the inlet and exhaust passage-ways extending through the shaft, the port B^c, the port B^d, the port B^e, and port B^f and port B^g designed to coact with the inlet and exhaust ports extending through the two portions of the double cylinder, the rotatable cylinder concentric to the shaft, the division-ring situated between the two ends of the cylinder and forming two crescent-shaped steam-chambers, the radial wings, means for imparting a radial movement thereto to follow the periphery of the solid cylinder in their rotation, the pipe extension of the shaft, the shoulder thereon, the threaded collar fitting against the shoulder and provided with a handle and the coacting collar fitting against the aforesaid collar and also provided with a handle for adjustment as and for the purpose specified.

7. In a rotary engine, the combination with

the eccentric inner portion of the casing and
the concentric outer portion forming a cres-
cent-shaped steam-chamber, of the pistons,
the stationary eccentrics on the shaft, the
straps surrounding the eccentrics and the
rods connecting them to the ends of the pis-
tons whereby such pistons in their rotation

are made to follow the periphery of the ec-
centric inner portion as and for the purpose
specified.

ALFRED KITCHEN.
